UNITED STATES PATENT OFFICE.

FRANK A. SHIMANS, OF CHICAGO, ILLINOIS.

RAZOR-HONE.

1,210,221.

Specification of Letters Patent. Patented Dec. 26, 1916.

Application filed April 20, 1916. Serial No. 92,369.

To all whom it may concern:

Be it known that I, FRANK A. SHIMANS, a citizen of the United States, and a resident of the city of Chicago, county of Cook, and 5 State of Illinois, have invented certain new and useful Improvements in Razor-Hones, of which the following is a specification.

My invention relates to improvements in razor hones, and has for its object the production of a device of this character through 10 the medium of which circular blades may be sharpened with ease and expedition.

A further object is the production of a razor blade sharpening device which will 15 be of simple construction and efficient in use.

Other objects will appear hereinafter.

With these objects in view, the invention consists in the combinations and arrangements of parts hereinafter described and 20 claimed.

The invention will be best understood by reference to the accompanying drawing forming a part of this specification, and in which,

25 Figure 1 is a side elevation of a razor hone embodying the invention, Fig. 2 is a top plan view thereof, and Fig. 3 is a vertical transverse section of the device.

The preferred form of construction, as 30 illustrated in the drawing, comprises a pair of spaced parallel sharpening elements 1 and 1' which are mounted in an elongated support 2 which is in the form of a trough supported at its ends upon legs 3. Coöperating with the support 2 is a second support 4 of substantially channel form, the support 4 being provided with projections 35 5 at its ends which slidably engage with elongated slots 6 formed in the legs 3 where- 40 by the support 4 may be shifted transversely relative to the support 2. The member 4 serves as a support for a plurality of spaced blade holders or shafts 7 which extend transversely of the device. Corresponding ends 45 of said blade holders are rotatably mounted in the side wall 4' of the support 4, the opposite ends of said blade holders releasably engaging with upwardly opening slots or notches 8 formed in the upper edge of the 50 opposite wall 4''. The last mentioned ends of blade holder 7 are releasably locked in engagement with the slots 8 by means of an elongated bar 9 one end of which is hinged at 10, the opposite end thereof being releasably locked in operative position by means 55 of a thumb screw 11.

The blades 12 are secured to the blade holders 7 by means of nuts 13, the arrangement being such that when said blades are arranged upon said holders, the lower portions of said blades will be positioned between the sharpening elements 1 and 1'. Rotation of the holders 7 and hence of blades 12 carried thereby is effected by means of bevel gears 14 provided upon the 60 holders 7 which mesh with bevel gears 15 provided upon a shaft 16 which is mounted in bearings projecting laterally from the wall 4' of support 4. With this arrangement, it will be seen that when the shaft 16 is rotated, as through the medium of a crank 17, all of the blades 12 will be simultaneously rotated.

Arranged below the support 4 are two cams 18 fixed to a shaft 19 which is mounted at its ends in the legs 3. The cams 18 engage with slotted lugs 20 which depend from the support 4 so that, upon rotation of shaft 19, said support and hence the blades 12 carried thereby will be moved transversely. With this arrangement, it will be seen, that by simply rotating the shaft 19, as through the medium of a crank 21 provided at one end thereof, the blades 12 may be moved to engagement with either of the 65 sharpening elements 1 or 1' in order to effect proper sharpening of the blades which, of course, may only be effected through engagement with both sides of the same. With this arrangement then, it will be seen, 70 that in the sharpening operation, the blades will be intermittently shifted to engage first with one sharpening element and then with the other, the same being rotated in engagement with said sharpening elements by operation of crank 17.

The side wall 4' of the support 4 is hinged as at 22 so as to permit of outward swinging of the same to carry the remote ends of blade holders 7 upwardly from engagement with the wall 4'' when the locking bar 9 is swung to releasing position. This arrangement is adopted in order to facilitate application of the blades to the holder 7 or removal of the same therefrom, it being clear that with the construction set forth, application or removal may be very easily and quickly effected.

While I have illustrated and described the preferred form of construction for carrying my invention into effect, this is capable of variation and modification without

departing from the spirit of the invention. I, therefore, do not wish to be limited to the precise details of construction set forth, but desire to avail myself of such variations and 5 modifications as come within the scope of the appended claims.

Having described my invention what I claim as new and desire to secure by Letters Patent is:

- 10 1. A razor hone comprising a pair of spaced sharpening elements; a support for said sharpening elements; a plurality of rotatable holders for the blades to be sharpened arranged above said sharpening elements and extending transversely thereof; a support for said holders mounted for transverse shifting relative to said first mentioned support, whereby the blades may be carried into engagement with either of said 15 sharpening elements; means for shifting said second mentioned support; and means for simultaneously rotating all of said blade holders, substantially as described.
- 20 2. A razor hone comprising a pair of spaced sharpening elements; a support for said sharpening elements; a plurality of rotatable holders for the blades to be sharpened arranged above said sharpening elements and extending transversely thereof; a support for said holders mounted for transverse shifting relative to said first mentioned support, whereby the blades may be carried into engagement with either of said 25 sharpening elements; means for shifting said second mentioned support; means for releasably mounting in operative position the ends of said blade holders at one side of said second mentioned support, the opposite ends of said blade holders being mounted in the opposite side of said support, said last mentioned side of said support being hingedly mounted, substantially as described.
- 30 3. A razor hone comprising a pair of spaced sharpening elements; a support for said sharpening elements; a plurality of rotatable holders for the blades to be sharpened arranged above said sharpening elements and extending transversely thereof; a support for said holders mounted for transverse shifting relative to said first mentioned support, whereby the blades may be carried into engagement with either of said 35 sharpening elements; means for shifting said second mentioned support; means for simultaneously rotating all of said blade holders, said last mentioned means comprising a shaft extending along said second mentioned support; and a gear connection between said 40 shaft and all of said blade holders, substantially as described.
- 40 4. A razor hone comprising a pair of spaced sharpening elements; a support for said sharpening elements; a plurality of rotatable holders for the blades to be sharpened arranged above said sharpening elements and extending transversely thereof; a support for said holders mounted for transverse shifting relative to said first mentioned support, whereby the blades may be carried into engagement with either of said 45 sharpening elements; means for shifting said second mentioned support; means for releasably mounting in operative position the ends of said blade holders at one side of said second mentioned support, the opposite ends of said blade holders being mounted in the opposite side of said support, said last mentioned side of said support being hingedly mounted; means for simultaneously rotating all of said blade holders, said last mentioned means comprising a shaft extending along and mounted upon said hinged side of said second mentioned support; and a gear connection between said shaft and all of said blade holders, substantially as described.

transverse shifting relative to said first mentioned support, whereby the blades may be 50 carried into engagement with either of said sharpening elements; means for shifting said second mentioned support; means for simultaneously rotating all of said blade holders; and means for releasably mounting in operative position the ends of said blade holders at one side of said second mentioned support, the opposite ends of said blade holders being mounted in the opposite side of said support, said last mentioned side of said support being hingedly mounted, substantially as described.

4. A razor hone comprising a pair of spaced sharpening elements; a support for said sharpening elements; a plurality of rotatable holders for the blades to be sharpened arranged above said sharpening elements and extending transversely thereof; a support for said holders mounted for transverse shifting relative to said first mentioned support, whereby the blades may be carried into engagement with either of said sharpening elements; means for shifting said second mentioned support; means for releasably mounting in operative position the ends of said blade holders at one side of said second mentioned support, the opposite ends of said blade holders being mounted in the opposite side of said support, said last mentioned side of said support being hingedly mounted; means for simultaneously rotating all of said blade holders, said last mentioned means comprising a shaft extending along and mounted upon said hinged side of said second mentioned support; and a gear connection between said shaft and all of said blade holders, substantially as described.

In testimony whereof I have signed my name to this specification in the presence of 90 two subscribing witnesses.

FRANK A. SHIMANS.
